ELECTRICAL OUTLET FOR ATTACHMENT TO THE ALTERNATOR OF AN AUTOMOBILE OR THE LIKE

Hollis R. Snodgrass, 601 S. Grinnell,
Perryton, Tex. 79070

Filed Mar. 28, 1972, Ser. No. 239,011

Term of patent 14 years

Int. Cl. D13—03

U.S. Cl. D26—15 A

Fig. 1.

Fig. 2.

Fig. 3.

Fig. 4.

Fig. 5.

Fig. 6.

Fig. 7.

FIG. 1 is a perspective view of an electrical outlet for attachment to the alternator of an automobile or the like showing my new design with the cover open;

FIG. 2 is a left side elevational view thereof with the cover closed;

FIG. 3 is a rear elevational view thereof with the cover closed;

FIG. 4 is a bottom plan view thereof to a reduced scale;

FIG. 5 is a top plan view thereof to a reduced scale;

FIG. 6 is a right side elevational view thereof to a reduced scale with the cover closed; and

FIG. 7 is a front elevational view thereof to a reduced scale with the cover closed.

The broken lines in the drawing are for illustrative purposes only.

I claim:

The ornamental design for an electrical outlet for attachment to the alternator of an automobile or the like, as shown and described.
